US00D804639S

(12) **United States Design Patent** (10) **Patent No.:** **US D804,639 S**
(45) **Date of Patent:** **** Dec. 5, 2017**

(54) **CEILING FAN**

(71) Applicant: **HUNTER FAN COMPANY**,
Memphis, TN (US)

(72) Inventor: **Benjamin Scotti Guthrie**,
Germantown, TN (US)

(73) Assignee: **Hunter Fan Company**, Memphis, TN
(US)

(**) Term: **15 Years**

(21) Appl. No.: **29/558,301**

(22) Filed: **Mar. 16, 2016**

(51) LOC (10) Cl. **23-04**

(52) U.S. Cl.

USPC **D23/377**; D26/59

(58) **Field of Classification Search**

USPC D23/355, 370-376, 378-387, 412, 414,
D23/377, 411, 413; D26/59; D12/214

CPC F04D 25/088; F21V 33/0096

See application file for complete search history.

(57) **CLAIM**

The ornamental design for a ceiling fan, as shown and described.

DESCRIPTION

FIG. 1 is a top perspective view of a ceiling fan showing my new design;

FIG. 2 is a bottom perspective view of the ceiling fan of FIG. 1;

FIG. 3 is a top view of the ceiling fan of FIG. 1;

FIG. 4 is a bottom view of the ceiling fan of FIG. 1;

FIG. 5 is a front side view of the ceiling fan of FIG. 1;

FIG. 6 is a right side view of the ceiling fan of FIG. 1;

FIG. 7 is a rear side view of the ceiling fan of FIG. 1; and,

FIG. 8 is a left side view of the ceiling fan of FIG. 1.

Portions of the ceiling fan shown in broken lines form no part of the claimed design.

1 Claim, 8 Drawing Sheets
